VIRGINIA HELSLEY, OF NEW YORK, N. Y., ASSIGNOR TO CHASE BRASS & COPPER CO.
INCORPORATED, OF WATERBURY, CONNECTICUT, A CORPORATION OF NEW YORK

DESIGN FOR A BRACKET MEMBER FOR BATHROOM FIXTURES

Application filed December 11, 1930. Serial No. 37,946. Term of patent 7 years.

To all whom it may concern:

Be it known that I, VIRGINIA HELSLEY, a citizen of the United States, residing at New York, in the county of New York and State of New York, have invented a new, original, and ornamental Design for a Bracket Member for Bathroom Fixtures, of which the following is a specification, reference being had to the accompanying drawing, forming part thereof.

The figure is a perspective view of a bracket member for bathroom fixtures showing my new design.

I claim:

The ornamental design for a bracket member for bathroom fixtures as shown.

VIRGINIA HELSLEY.
